4 Claims. (Cl. 332—23)

This invention relates to a frequency modulation circuit, and more particularly to a frequency modulation circuit which may be applied to video tape recorders. According to this invention, a frequency modulated signal may be obtained having a smaller amplitude modulation component (AM component), and a superfluous side-band wave in the frequency modulated signal may also be removed; thus a frequency modulated signal having a minimum of spurious components may be obtained.

Accordingly, one object of this invention is to provide a frequency modulation circuit in which a frequency modulated signal having a carrier of low frequency, such as 2 mc./s., may be obtained.

Another object of this invention is to provide a frequency modulation circuit in which two variable frequency oscillators are provided whose center oscillation frequencies are different from each other, and whose said oscillation frequencies are deviated respectively higher and lower than their fundamental undeviated oscillation frequencies in response to an input signal; whereby two frequency modulated signals are obtained from the two oscillators and these signals are mixed to produce a final frequency modulated signal which is the difference between the above two signals. In this way sensitivity for frequency modulation is greatly increased and frequency modulation of good linearity is effected.

Another object of this invention is to provide a frequency modulation circuit in which two variable frequency oscillators including variable capacity elements are provided, and the capacities of the variable capacity elements are respectively varied by a video signal to obtain an oscillation frequency signal in accordance with the video signal, namely a frequency modulated signal. Thus the non-linear characteristic caused by the use of only a single variable capacity element, as in heretofore known modulators, is completely compensated.

Another object of this invention is to provide such a frequency modulation circuit in which a video signal is arranged to be applied to a variable capacity element through a resonance circuit tuned to a frequency equal to center frequency of the oscillator and an undesired side-band wave of an input signal is filtered out by such resonance circuit.

A further object of this invention is to provide a circuit in which two frequency modulated signals are produced by two variable frequency oscillators and they are mixed by a transistor to produce a low carrier frequency modulated signal, and band-pass filters are provided at the output sides of the variable frequency oscillators. Thus second or higher harmonic waves and second or higher-order side band waves in the frequency modulated signal may be removed. That is, when obtaining a low frequency modulated signal by mixing, spurious modulation products are prevented from appearing in the output signal.

Yet a further object of this invention is to provide a transistorized modulator which is simple in construction and of small power consumption.

2

Other objects, features and advantages of this invention will become apparent from the following description taken in conjunction with the accompanying drawings, in which:

5 FIGURE 1 is a circuit diagram illustrating an example of the frequency modulation circuit according to this invention;

FIGURES 2A and 2B are graphs illustrating the relations of capacitance and oscillation frequency to the bias voltage of a variable capacity element;

10 FIGURES 3A and 3B are frequency spectrum diagrams; and

FIGURE 4 shows the attenuating characteristics of a band-pass filter.

15 Referring to FIGURE 1, 1A and 1B are video input signal terminals and 2 is a video amplifier. Between output terminals 3a and 3b of the amplifier 2, there is a positive-polarity video signal 4 of maximum peak to peak voltage (the level of a synchronizing pulse being at low voltage), for example of 2 v.

At the output of the video amplifier 2 are provided two variable frequency oscillation circuits, namely frequency modulation circuits designated by numerals 5a and 5b. The variable frequency oscillation circuit 5a is provided 25 with a transistor 6a, its collector being connected to the base through an inductor 7a having an inductance of, for instance 0.79 micro henry and a capacitor 8a having a capacitance of, for example 50.0 pf. and being grounded through a capacitor 9a of 50.0 pf. and a semiconductor diode type variable capacity element (varactor) 10a usually referred to by the trademark "Vari-Cap," while its base is grounded through a variable capacitor 11a having a capacitance of, for example 25 pf. at maximum; its emitter being also grounded through a resistor 12a and a band-pass filter 15a composed of an inductor 13a and a capacitor 14a. It is known that the variable capacity element 10a has a characteristic relationship of capacitance C_a to bias voltage V_a such as shown by the curve 16a in FIGURE 2A. The band-pass filter 15a has the band-pass characteristic of, for instance from 50.0 mc./s. to 55.0 mc./s., though this will be clarified later herein,

30 The mid-point 17a of the inductor 7a is connected through a high-frequency choke coil 18a to a DC voltage terminal 19 of +12 v., and the base is connected through a high-frequency coil 20a to the connecting mid-point of voltage-divider resistors 21a and 22a connected between the DC voltage terminal 19 and ground. A bias voltage of, for example —3.5 v. is applied across the variable capacity element 10a in the reverse direction. 23a is a bias 35 supply power source terminal.

35 The oscillation circuit 5a is a Colpitts or Clapp type oscillation circuit, which is so formed as to oscillate at a standard frequency f_{a1} of, for instance 52.2 mc./s. by adjusting the capacitance of the capacitor 11a when there are no input signals. An output terminal 3a of the video amplifier 2 is connected to the variable capacity element 10a through an inductor 24a having an inductance of, for example 1 μ h. Together with its stray capacity 25a, the inductor 24a forms a resonance circuit 30a which substantially resonates to the center oscillation frequency f_{a1} ($f_{a1}=52.2$ mc./s.) of the oscillator 5a.

40 The other variable frequency oscillation circuit 5b is substantially the same as the aforesaid variable frequency oscillation circuit 5a. Accordingly, parts corresponding to those of the circuit 5a are marked with the same reference numerals with the suffix *b* instead of the suffix *a*, and to that extent further detailed explanation

will not be necessary. It must be noted however that in this case the anode of the variable capacity element 10b has been connected through a resonance circuit 30b to the terminal 3a, and its cathode has been grounded through a capacitor 42b.

Connected in parallel to a charging capacitor 26b is a Zener diode 27b, to which a DC voltage source 28 is connected. Thus, if a constant voltage of, for example 9 v. is applied across the charging capacitor 26b, a stable bias voltage of say -5.5 v. with reverse direction is applied across the variable capacity element 10b. Furthermore, the capacitance of the capacitor 11b is so adjusted that the center oscillation frequency f_{b1} of the variable frequency oscillation circuit 5b is selected to be, for instance 50.0 mc./s. Therefore, the resonant frequency of the resonance circuit 30b formed by the inductor 24b is also selected at about 50.0 mc./s. In FIGURE 2B, 16b is a curve of the capacitance C_b of the variable capacity element 10b in relation to the voltage (-Vb).

Operation of the aforementioned variable frequency oscillator, namely the frequency modulation circuit 5a, will now be explained. When a signal 4 of a maximum peak to peak value of, for example, 2 v. with positive polarity is applied to the variable capacity element 10a as described above, there is obtained at the output terminal of the band-pass filter 15a an oscillation frequency f_{a1} of 52.2 mc./s. at the peak level of a synchronizing pulse, and an oscillation frequency f_{a2} of, for example 52.9 mc./s. is obtained at a maximum value 2 v. of white level of the video signal. This relation will be understood from the curve 16a of the voltage (-) V_a against the frequency f in FIGURES 2A. Consequently the oscillation frequency of the variable frequency oscillator 5a is deviated from 52.2 mc./s. to 52.9 mc./s. in response to the input video signal.

In the other variable frequency oscillator 5b, there are produced an oscillation frequency f_{b1} of 50.0 mc./s. at the peak level of the video signal 4, and an oscillation frequency f_{b2} of 49.3 mc./s. at the maximum value of 2 v. of white level; that is, the oscillation frequency is deviated from 50.0 mc./s. to 49.3 mc./s. in accordance with the input signal. This relation will be apparent from the curve 16b of the voltage (-) V_b against the frequency f_b in FIGURE 2B.

In this case, as is apparent from FIGURE 2A, the capacitance C_a of the variable capacity element 10a decreases with an increase in the voltage of the video signal 4, and as the result the oscillation frequency f_a of the variable frequency oscillator 5a increases. However, it must be noticed that such decrease in the capacitance C_a causes a decrease in the oscillation output voltage or power of the transistor 6a. Accordingly, the frequency modulated output signal f_a of the variable frequency oscillator 5a will include a component having amplitude-modulation in response to the voltage of the video signal 4. On the other hand, however, the frequency f_a vs. the impedance characteristic of the resonant circuit 30a composed of the inductor 24a and stray capacitance 25a is such that as the oscillation frequency f_a becomes higher than the resonance frequency f_{a1} , its effective capacitance increases. Therefore the impedance between the collector and emitter of the transistor 6a is so compensated as to be substantially constant with respect to the oscillator frequency. This is because the variable capacity element 10a and the resonance circuit 30a have been in effect connected in parallel between the collector and emitter, with respect to the oscillator frequency. With such an arrangement, it is clear that no component having amplitude modulation in accordance with the input signal is mixed into the modulated frequency signal f_a .

It will also be understood from the foregoing that a frequency modulated signal without any amplitude-modulated component is likewise obtained from the variable frequency oscillation circuit 5b.

The two signals f_a and f_b having been frequency-

modulated as described above, are taken out respectively at the output terminals 29a and 29b of the band-pass filters, 15a and 15b. In the foregoing, it was shown that there are obtained at the output terminals 29a and 29b the frequency signals f_a and f_b respectively having frequency deviations of 52.2 to 52.9 mc./s. and 50.0 to 49.3 mc./s. The frequency swing of the video signal 4 is given by a maximum frequency deviation Δf , namely

$$\frac{f_{a2} - f_{a1}}{2}$$

or

$$\frac{f_{b1} - f_{b2}}{2}$$

In the present example $\Delta f = 0.35$ mc./s., and hence the center frequencies f_{a0} and f_{b0} of the oscillators 5a and 5b are given by 52.55 mc./s. and 49.65 mc./s. respectively. Consequently there are contained in the frequency modulated signal f_a of the oscillator 5a, side band wave components of $(f_{a0} \pm \Delta f) \pm f_m$, $(f_{a0} \pm \Delta f) \pm 2f_m$, $(f_{a0} \pm \Delta f) \pm 3f_m$

such as shown in FIGURE 3A, other than the component of $(f_{a0} \pm \Delta f)$, where the maximum frequency of the video signal, generally between 3 to 4 mc./s., is f_m . Similarly there have been included in the frequency modulated signal components of $(f_{b0} \pm \Delta f)$, $(f_{b0} \pm \Delta f) \pm f_m$, $(f_{b0} \pm \Delta f) \pm 2f_m$

such as shown in FIGURE 3B. The primary component f_m is indispensable for transmitting broadband video signals, but second and higher harmonics are unnecessary, since when the frequency modulated signals f_a and f_b of the oscillators 5a and 5b are mixed as described later, lapped components of the higher side band wave components are so mixed that no faithful low carrier frequency modulated signal is obtained. Therefore the band-pass filters 15a and 15b are necessary, so as to remove the second or higher side band wave components with respect to f_m from the frequency modulated signals. The staggered and overlapping attenuation characteristics of the band-pass filters are illustrated by the curve 41a and 41b in FIGURE 4, and the pass bands are selected to be from 50 to 55 mc./s. and from 47 to 52 mc./s. respectively.

The two frequency modulated signals f_a and f_b thus obtained are applied to a mixer circuit 31. The mixer circuit 31 is provided with a transistor 32 and may be formed by connecting the output terminal 29a through a coupling condenser 33 to the base of the transistor 32, and the output terminal 29b to the emitter. 34 and 35 are resistors for base biasing, 36 is a resistor for the collector and 37 is a resistor for the emitter. To the output of the mixer circuit 31 is connected a low-pass filter 38 of, for example, from 0 to 15 mc./s. passband. Between the base and emitter of the transistor 32 of the mixer circuit 31, the frequency signals f_a and f_b from the oscillation circuits 5a and 5b are mixed with each other, and thus a low carrier frequency modulated signal f_{ab} of a band pass range of about 6 mc./s. or less is obtained at the output end of filter 38. This frequency modulated signal f_{ab} is supplied to an output terminal 40 through an amplifier 39 and thence to a magnetic head, whereby the low carrier frequency modulated signal can be recorded on a magnetic recording medium.

In this system the low carrier frequency modulated signal f_{ab} is taken out differentially due to beating-down by mixing the high frequency modulated signals f_a and f_b from the two modulation circuits 5a and 5b, and hence even if non-linearities appear in the variable capacity elements 10a and 10b, they are compensated by each other so that a low frequency modulated signal of favorable linearity with respect to the video signal may be obtained.

As two such modulation circuits 5a and 5b have been

employed, the frequency deviation range in this case may be reduced by half as compared with that of a conventional modulation circuit. Therefore, the present invention is especially characterized in that variable capacity varactor diode elements and transistors may be used in combination in a range of good linearity.

A list of suitable circuit values which may be used to construct an operative circuit as above described is as follows.

Inductors:

13a, 13b	microhenries	0.5
17a, 17b	do	0.79
18a, 18b	do	10.0
20a, 20	do	20.0
24a	do	1.0
24b	do	3.0

Capacitors:

8a, 8b, 9a, 9b	picofarads	50
11a, 11b	max. picofarads	25
14a, 14b	do	45
26b	microfarads	20
33	picofarads	100
42b	do	500

Resistors (values in kilo ohms unless otherwise specified):

12a, 12b	ohms	330
21a, 21b		6.8
22a, 22b		1.8
34		27
35		4.7
36		1.0
37	ohms	120
43b		1.0

The foregoing description has been made in connection with an example in which a variable frequency oscillation circuit, namely a frequency modulation circuit, has been composed of a Colpitts-like oscillation circuit, but a Clapp oscillation circuit may also be utilized. Furthermore, it will easily be seen that the two standard frequencies and the frequency deviation ranges therefrom may be varied at will. It will also be understood that the resonance circuit shown as including an inductor for preventing an amplitude modulated component from being produced may be formed of a lumped constant element, and that the band-pass filters may be formed as desired.

It will be apparent that many modifications and variations may be effected without departing from the scope of the novel concept of this invention.

What is claimed is:

1. A frequency modulation circuit characterized by reduced amplitude modulation and side-band components in its output, comprising two variable oscillators of different unmodulated oscillation frequencies, each of said two variable oscillators including a transistor having a base, a collector and an emitter, and a voltage-variable capacitance element inserted in a circuit including the collector and emitter of each of said transistors, input means for applying identical input signals to both of said two variable capacitance elements, respective tuned circuits resonated near the respective unmodulated frequencies of said oscillators and connected between said input means and said transistors in such a way that they are, at the respective oscillation frequencies, connected effectively in parallel relationship to the respective vari-

able capacitance elements as seen from the collector and emitter of said respective transistors, one of the two variable oscillator frequencies being increased in response to said input signals, while the other is decreased in response to said same input signals, the effective input impedance as seen between the collector and emitter of each transistor being thereby maintained substantially constant with respect to changes in the oscillator frequencies, output means for obtaining a pair of frequency modulated signals from said oscillators, and a mixer circuit for mixing the pair of frequency modulated signals from the output means to provide a frequency modulated signal substantially free from amplitude modulation and the frequency of which is equal to the difference between the frequencies of said pair of frequency modulated signals.

2. A frequency modulation circuit as claimed in claim 1, wherein the variable capacitance elements included in the respective oscillators are connected with opposite polarities to each other with respect to the input means.

3. A frequency modulation circuit as claimed in claim 1, wherein said mixer circuit includes at least one transistor to the emitter and the base of which the frequency modulated signals of said respective output means are respectively supplied.

4. A frequency modulation circuit characterized by reduced amplitude modulation and side-band components in its output, comprising an input terminal for connection to a source of modulating signals, a pair of frequency-deviable oscillators having different center frequencies and each including a pair of frequency-control terminals, respective frequency-deviating variable-capacitance semiconductor devices connected with opposite polarities in frequency controlling relationship relative to said control terminals, a resonant frequency control connection between said input terminal and each respective one of said devices, said connections including resonant frequency elements tuned to the respective center frequencies of said oscillators, a mixer circuit, stagger-tuned resonant band-pass circuits connected between the outputs of said respective oscillators and the input terminals of said mixer circuit, said band-pass circuits having pass bands which overlap at the desired output center frequency, and a low-pass filter connected to the output of said mixer circuit, whereby the output signal from said low-pass filter is substantially a pure low-sideband-plus-fundamental frequency-modulated carrier; said resonant circuits being effectively in parallel with said respective devices with reference to the frequency-control terminals of said oscillators, so as to compensate for voltage changes across said terminals reflected from frequency changes.
